CLAIM

The ornamental design for a portable cooler, as shown and described.

DESCRIPTION

FIG. 1 is a side-top perspective view of a portable cooler showing our new design;

FIG. 2 is a first side elevational view of the portable cooler shown in FIG. 1;

FIG. 3 is a second side elevational view of the portable cooler shown in FIG. 1;

FIG. 4 is a rear elevational view of the portable cooler shown in FIG. 1;

FIG. 5 is a front elevational view of the portable cooler shown in FIG. 1;

FIG. 6 is a top plan view of the portable cooler shown in FIG. 1;

FIG. 7 is a bottom plan view of the portable cooler shown in FIG. 1; and,

FIG. 8 is a bottom-side perspective view of the portable cooler shown in FIG. 1.

The broken line portions of the drawing figures are included to show unclaimed subject matter only and form no part of the claimed design.

1 Claim, 5 Drawing Sheets
